UNITED STATES PATENT OFFICE.

CHARLES W. POST, OF ZION CITY, ILLINOIS.

COMBINED PROPELLING AND STEERING APPARATUS FOR BOATS.

No. 817,985.

Specification of Letters Patent.

Patented April 17, 1906.

Application filed July 3, 1905. Serial No. 268,219.

To all whom it may concern:

Be it known that I, CHARLES W. Post, a citizen of the United States, residing at Zion City, in the county of Lake and State of Illinois, have invented certain new and useful Improvements in a Combined Propelling and Steering Apparatus for Boats, of which the following, when taken in connection with the drawings accompanying and forming a part hereof, is a full and complete description sufficient to enable those skilled in the art to which it pertains to understand, make, and use the same.

This invention is particularly designed to provide means for propelling small boats in any desired direction and in shallow water, although it is equally well adapted to propel large boats in any desired direction in deep water.

I have illustrated the machine embodying this invention in the drawings referred to, in which—

Figure 1 is a side elevation of the apparatus, and Fig. 2 is a vertical section of the apparatus.

A reference-letter applied to designate a given part is used to indicate such part throughout both the figures of the drawings wherever the same appears.

30 A is the shell or casing of the apparatus, and *a* is a flange by means of which the shell is attached to the bottom of a boat, on the inside thereof, with the part *a'* extending through the bottom of such boat to underneath the bottom thereof.

35 *a''* is a screw-threaded aperture in shell A, to which is attached a water-pipe from a pump or other water-forcing apparatus, by means of which water can be forced into shell A.

40 B is a rotatable plug in shell A. Plug B extends above shell A, and steering-wheel C is rigidly attached thereto. Plug B is provided with shoulders D E, the shoulder D

45 resting on a corresponding shoulder in the lower end of shell A and shoulder E, positioned to receive thereon the corresponding shoulder in cap F of shell A. Cap F is screw-threaded, as at *f*, such screw-threads engag-

ing with like screw-threads at the upper end 50 of shell A.

G is packing in shell A adjacent to cap F.

The lower end of the plug B is provided with passage-way H, such passage-way being curved and contracted, as at *h*, at its lower end 55 and at its upper end communicating with the chamber I in shell A through apertures J J.

As will be seen on observing Fig. 2 of the drawings, when water is forced into the chamber I through the aperture *a''* such water will 60 flow through the apertures J J into passage-way H and out therefrom through aperture *h* in a substantially horizontal plane. By turning the plug B by means of steering-wheel 65 C the direction of the stream flowing from aperture *h* will be changed.

The boat will be moved by the flow of water from the aperture *h* into the body of water in which the boat floats, and by the turning of the plug B in a proper manner the boat 70 will be guided in any desired direction.

Having thus described my invention and the construction of an apparatus embodying the same and the manner of operation thereof, what I claim as new, and desire to secure 75 by Letters Patent, is—

The combination of a shell provided with a passage-way therethrough, a shoulder at the lower end of the passage-way and such passage-way enlarged to form a chamber, and 80 such shell provided with an aperture therethrough communicating with the chamber, a plug rotatably mounted in the shell and extending below it, such plug provided with a shoulder corresponding with and resting on 85 the shoulder in the shell, and such plug provided with a passage-way communicating with the chamber in the shell and with the water below the shell, the discharge of such passage-way directing the water flowing 90 therethrough in a substantially horizontal plane, and a steering-wheel attached to the rotatable plug, substantially as described.

CHARLES W. POST.

In presence of—

CORA A. ADAMS,

CHARLES TURNER BROWN.
